UNITED STATES PATENT OFFICE.

JOHN JOSEPH COOPER, OF LONDON, ENGLAND, ASSIGNOR TO UNDERWOOD TYPE-WRITER COMPANY, OF NEW YORK, N. Y., A CORPORATION OF NEW JERSEY.

TYPE-WRITING MACHINE.

1,068,325.

Specification of Letters Patent.

Patented July 22, 1913.

Application filed July 30, 1909. Serial No. 510,373.

To all whom it may concern:

Be it known that I, JOHN JOSEPH COOPER, a subject of the King of Great Britain, residing in the city of London, England, have 5 invented certain new and useful Improvements in Type-Writing Machines, of which the following is a specification.

This invention relates to typewriters, and has for its object to provide an instrument 10 by means of which a series of figures, letters or other signs may be successively impressed upon a narrow ribbon of paper or tape, and especially for preparing drafts by textile designers for use in setting up the designs 15 for weaving, and more especially for the use of the weaver in controlling the grade, shade or color of the woof or filling thread.

The invention provides an improved means for preparing a woof color design 20 draft or tell-tale strip to be used in setting up the loom or more often to go along with the actual weaving operation.

The woof draft or tell-tale strip is in the form of a long strip of paper having a series of numbers arranged in a column 25 extending lengthwise of the strip, each number consisting of one or more digits.

The typewriter, which forms the subject-matter of this invention, is used to typewrite 30 the numbers in a column extending lengthwise of the tell-tale strip.

The usual letter-spacing mechanism is preferably entirely omitted from the machine; and two distinct sets of numeral keys 35 are employed, one set for writing in the tens column and the other set for writing in the units column; each set of keys having its own set of type bars; and the types being so placed that the numbers will appear in the 40 desired order upon the strip.

Line feeding of the strip is effected by a bar or key, which corresponds to the usual space key in ordinary typewriting machines. The space bar is connected to a pawl adapted 45 to coact with a ratchet wheel on the platen so that when the space bar is struck a motion or partial rotation is imparted to the platen. The platen is connected to drive a spool upon which the strip is wound after 50 being written upon. The platen is also connected to a counter or indicator which turns up a number each time the space bar is actuated, giving the number of complete numbers written, if a number is written for

each line, or in other words, giving the number of pick threads passed at any point. 55

The usual movable carriage for side spacing is dispensed with and a ribbon of paper or tape for receiving impressions is fed in one direction only by means of the space bar 60 and independently of the keys, impressions being effected when the keys are struck.

One form of machine constructed in accordance with this invention and adapted for writing a series of figures from 1 to 99, 65 is provided with two sets of keys and type-bars, one set for the units and one set for the tens and each set of bars has a corresponding guide so that a units key and a tens key may be struck simultaneously. The 70 platen is of the usual form but is capable of rotation only so that when the keys are struck no motion is imparted thereto.

Referring to the drawings, Figure 1 is a side elevation of one form of machine constructed in accordance with this invention and adapted for writing a series of figures from 1 to 99. Fig. 2 is a front elevation. Fig. 3 is a plan thereof.

Duplicate keyboards comprising two sets 80 of keys *a*, *b*, and type bars of the usual kind are provided, one set *A* for the units and one set *B* for the tens and each set of bars has a corresponding guide *c*, *d*, respectively so that one of the keys *a* and one of the keys *b* 85 may be struck simultaneously. The keys are mounted as usual on levers *A'*, which are connected by sub-levers *A''* to the type bars in the manner usual in the Underwood front strike typewriting machine; and all the type 90 bars in both sets may be mounted on one fulcrum wire as in said Underwood machine; but they are constructed so that one set strikes through one type guide and the other set strikes through the other type 95 guide.

e is a platen of usual form, but is capable of rotation only so that when the keys are struck no letter feeding motion is imparted thereto. A space bar *f* which is pivoted at *g* 100 is adapted when depressed to rock the arm *h* and through a link *m*, to operate the lever *j* pivoted at *z*. Pivoted to the lever *j* is an arm *n* carrying a spring-pressed pawl *o* adapted to engage a ratchet wheel *p* so that 105 depression of the space bar *f* causes partial rotation of the platen *e*, for line-feeding the strip.

A spool *q* mounted in bearings *r* on a frame *s* carries a supply of the ribbon *t* of paper or tape upon which the figures are to be printed. The ribbon *t* passes to the 5 platen *e* through a guide *u* having a roller *v* and is adapted to be wound on a spool *w* mounted in bearings *x* on the frame *s*. The spool *w* is driven by a chain wheel *y* mounted on the spindle of the platen *e* and a chain 10 *z* passing around said chain wheel *y* and around a second chain wheel *2* which is connected with the spindle *w¹* of the spool *w* by a collar *3* loose on the spindle *w¹* frictionally driven by said sprocket wheel *2*, 15 said collar *3* being resiliently connected by a coiled spring *3^a* to the collar *3^b* fastened on the spindle *w¹* so that the rotary motion of the sprocket wheel *2* is resiliently transmitted to the spindle *w¹*. In order to prevent the spring *3^a* from being overwound, dogs *3^c* on the collar *3^b* move in grooves in the collar *3* so that when said dogs engage the ends of their respective grooves the sprocket wheel *2* will slip over the collar *3*. 20

It sometimes happens that the same number should be repeated several times and it is not necessary to print such repetition but a corresponding length of ribbon may be fed through. This feed may be effected for 25 a short series by depressing the space bar *f* the required number of times but to conveniently effect such feed for a long series, a crank handle *4* is provided on the spindle of the platen *e* whereby said platen may be 30 revolved to feed forward the ribbon. To enable the desired length of ribbon to be fed an indicating device or counter *5* is driven by a spur wheel *6* mounted on the spindle of the platen *e* and meshing with 35 a pinion *7* on the device *5*.

Each figure in type is arranged on its lever according to its corresponding value, so that if a unit is to be struck the impressed figure will appear in the unit column and if 45 a ten is to be struck the ten figure will appear in the tens column.

In the use of the device with the indicating counter at "1" and the strip in position, the number designating the shade, 50 grade or color of the woof thread of the first pick is struck. If the number is less than ten, it is necessary to strike but one of the units keys; if greater than ten, a tens key as well as a units key must be struck. 55 The keys of the two sets may be struck at the same time or successively. At any rate, the strip remains stationary while the number is being written at this particular point, corresponding to the particular pick of the 60 fabric, whether this number contains one or two digits. The color in the first pick may run for a number of picks. Of course the number of the color could be repeated successively at each point, but generally it 65 would only be necessary to put the num-

bers at the points of change from one color to another. If the successive woof threads of the same color are few in number, the strip can be spaced up by the use of the space bar *f*; if, however, the number of picks of the same grade or color is great, the crank *4* is turned to bring the point on the strip corresponding to the first different pick up to the printing point. The counter 70 5 keeps track of the number of points or picks, so that the operator can tell at a glance the number of the pick without counting mentally. 75

It will thus be seen that a tell-tale strip or indicator can be made which will have numbers thereon to indicate the particular grade, shade or color of the woof threads at the different picks of the fabric. If the loom is of automatic shuttle type with but few changes, the strip can be used by the 80 designer or loom fixer to set the automatic shuttle control. If a large number of changes are necessary the strip can be arranged to be fed from the loom by a reel and ratchet mechanism, so that points on the strip will show up at the same time that the corresponding picks of the fabric are being woven, calling the weaver's attention to any changes in the grade, shade or color 85 of the woof threads necessary. The weaver can then accurately shift the shuttle box to bring the proper shuttle into action at the proper time. 90

Having thus described my invention, I 95 claim:

1. A machine of the character described, comprising a platen carrying a paper strip, two sets of type bars, the bars of one set mounted to strike at a different printing point from the bars in the other set, so that 100 the type impressions will be made side by side, in units and tens columns, two juxtaposed type guides, one for each set of type bars, two sets of keys for operating said type bars, the construction and operation of said 105 devices being such that the paper strip remains stationary during the operation of the keys, and means at the keyboard independent of said keys for line-feeding the paper strip. 110

2. A machine of the character described, comprising a platen carrying a paper strip, two sets of type bars, the bars of one set mounted to strike at a different printing point from the bars in the other set, so that 115 the type impressions will be made side by side, in units and tens columns, two juxtaposed type guides, one for each set of type bars, two sets of keys for operating said type bars, the construction and operation of said 120 devices being such that the paper strip remains stationary during the operation of the keys, means at the keyboard independent of said keys for line-feeding the paper strip, 125 said strip-feeding means comprising a 130

ratchet wheel connected to the platen, a pawl operated by the key at the keyboard, to engage said ratchet wheel and turn the platen, a winding spool for the paper strip, and a 5 connection from the platen to the winding spool.

3. The combination of a platen carrying a paper strip, a ratchet wheel connected to the platen, a pawl operated by the key at the 10 keyboard, to engage said ratchet wheel and turn the platen, a winding spool for the paper strip, and a connection from the platen to the winding spool.

4. The combination with a platen, of a 15 system of types to coöperate with said platen to write on a strip of paper and keys to operate the types, said system comprising two sets, the characters in each set of types being different from each other and having duplicates in the other set, the types in the two 20 sets being mounted to strike at points in horizontal alinement with each other, so that the same or different characters can be written in horizontal alinement with each other 25 while the strip of paper remains stationary, the two sets of types and keys being grouped together on opposite sides of the center of the machine.

5. The combination with a platen, of two 30 sets of type-bars, two juxtaposed type guides, one for each set of type-bars, types on the

type-bars, the types on one set of bars being duplicates of those on the other set, and right-hand and left-hand duplicate keyboards connected respectively to the two sets 35 of type-bars.

6. The combination of a rotary platen, means to support a work-strip or band thereon, type guides located side by side over the printing point, two sets of type-bars coöperating respectively with said type guides, right-hand and left-hand keyboards comprising finger keys and connected respectively to the type-bars of the two sets, said platen being stationary during the operation 40 of the keys, and a space key to rotate the platen and feed the work-strip.

7. The combination with a platen, of two sets of types, the types of the two sets being duplicates, and a keyboard comprising a 45 right-hand and a left-hand set of keys connected respectively to the two sets of types.

8. In a writing machine, the combination of a platen, two sets of type-bars on opposite sides of the center of the machine, duplicate 50 sets of types on the type-bars, and a right-hand and a left-hand set of finger keys connected respectively to said sets of type-bars.
